FREE-PLAY DEVICE

Harry E. Williams and Lyndon A. Durant, Chicago, Ill., assignors to A. B. T. Manufacturing Corp., Chicago, Ill., a corporation of Illinois

Application November 19, 1938, Serial No. 241,310

2 Claims. (Cl. 194—92)

This invention has as one of its principal objects the provision of repeat operating or free-play control mechanism for use in amusement apparatus of the type employing a coin-operated control, the arrangement being such that whenever a player achieves a certain score or objective, the free-play mechanism will be actuated to condition the coin-operated control for operation to free the game for another round of play without the necessity of depositing another coin in the control.

Viewed from another aspect, it is an important object of the invention to provide, in combination, a control device having detent means arranged to latch an actuating member or slide whenever the latter is manipulated without deposit of a coin therein, the presence of a coin preventing operation of the detent means so that the actuating member or slide may be effectively moved, and means including a movable stop member normally disposed in ineffective position near the detent means and movable into stopping relation to the detent means so that the latter cannot latch the actuating member or slide even though no coin is deposited in the latter, and electrically energized means operated, as a result of achieving a predetermined score or objective in playing the game, for moving the stop means into stopping position relative to the detent means so that the operating control may be actuated without deposit of a coin therein.

Another and more specific object is the combination, with a coin-operated control of the reciprocal slide variety, of free-play means including a dog arranged to project its nose into latching engagement with the slide when no coin is carried by the latter, and a stopping member mounted for movement from a normally ineffective position into position relative to the dog to prevent movement of the latter into latching position even though no coin is carried by the slide, and electromagnetic means for moving the stopping member into stopping position.

Other advantages and novel aspects of the invention reside in certain details of construction, arrangement of parts, and mode of operation of the illustrative embodiment hereinafter described in view of the annexed drawing, in which:

Fig. 1 is a fragmentary sectionalized perspective of a game apparatus employing the novel free-play means;

Fig. 2 is an enlarged transverse section through the coin control and free-play means, as viewed in the direction of line 2—2 of Fig. 1;

Fig. 3 is an enlarged vertical longitudinal section through the coin control and free-play means, as viewed in the direction of line 3—3 of Fig. 2;

Fig. 4 is a perspective of the coin control or slide and detent means; while

Fig. 5 is a circuit diagram and scheme of the free-play means.

In a preferred arrangement such as shown in Fig. 1, the free-play mechanism is utilized in conjunction with an amusement apparatus or game including a cabinet 18 having arranged therein an inclined playboard or field 11 in which there are one or more ball openings 12 through which balls or other projectiles projected onto the board by means well known in the art may become lodged to operate a control instrumentality, such as the switch 13, to close the contacts 14 and 15 thereof. The switches 13 are mounted on a sliding frame or shuffle member 16 having a pendent arm 17 engaged by the inner end 18 of an actuating control which, in this instance, is the reciprocable slide 19 of a coin chute 20.

The coin chute 20 is preferably of the familiar reciprocal slide variety including a frame or sleeve structure 21 projecting horizontally from a vertical mounting plate 22 and in which sleeve the slide 19 is mounted for a back and forth movement. The slide 19 (Fig. 4) is provided with a coin pocket 25 into which a suitable coin is deposited for movement by the slide within the plane of the same in a direction inwardly of the frame and slide member 21.

Means is provided in the form of a coin-operated detent for normally latching the slide against effective movement when no coin has been deposited in the pocket 25. In the preferred arrangement, the aforesaid detent means includes (Fig. 3) a dog pivotally mounted as at 31 on a depending ear 32 from the bottom sleeve portion 21 of the slide, this dog having a nose 33 opposite a tail 30, the nose projecting through an opening 34 upwardly for movement into the coin pocket

25, a spring 35 normally urging the dog to project its nose into the pocket to prevent effective inward movement of the slide. When a suitable coin is disposed in the pocket 25, it will be engaged by the nose of the dog so that said nose will be prevented from moving into latching or stopping engagement with the slide, and the latter may therefore be moved inwardly to the limit of its stroke whereupon the coin carried thereby will be automatically ejected from the pocket by means well known in the art.

The manner in which the latching nose 33 of the dog projects into the coin pocket to latch the slide is illustrated in Fig. 4.

When a suitable coin is deposited in the slide and the same is moved inwardly, the inner end portion 18 thereof engages the pendent member 17 on the shuffle frame and moves the latter to withdraw the switch or switches 13 from beneath their respective ball pockets or openings 12, so that any trapped balls may be freed for use in playing the game, the mechanism and means for effecting movement of the balls back onto the playfield not constituting part of the present invention and being so well known in the art that detailed description of the same herein is deemed unnecessary.

Assuming that the lodgement of a ball into the opening 12 of Fig. 1 constitutes the achievement of a particular score or objective in playing the illustrative game, it is an object of the invention to reward the achievement by conditioning the game for further play without deposit of a coin in the control slide, and means for accomplishing this includes the provision of a stop member in the form of a magnetically attractive arm 40 which is mounted in the region below the tail 30 of the dog or detent means (Figs. 1, 2, 3) for rocking movement into and out of the plane of the dog, the member 40 having a tail portion 41 which fits into a slot in a horizontally extending portion 42 of a mounting bracket 43 attached as at 44 on an inner wall of the cabinet beneath the coin slide.

Spring means 45 attached to the tail 41 and a lug 46 on the bracket yieldingly urges the stop member 40 into a normal position with its upper offset edge portion 47 disposed out of the plane of the dog and away from the tail 30 thereof, so that the latter is free to move in a vertical direction into and out of latching engagement with the coin slide.

Means for moving the stop member from ineffective into effective stopping position relative to the detent means includes the provision of an electromagnet 50 mounted on the bracket 43 with a pole opposite the magnetically attractive stop member 40 so that when the magnet is energized, the stop member will be moved into the dotted line position of Fig. 2 to dispose the offset marginal or edge portion 47 beneath the tail 30 of the dog or detent means, so that the latter will not be able to pivot and project its nose 33 into latching engagement or position relative to the control device or actuating slide 19.

The stop operating means or magnet 50 is preferably arranged in a free-play circuit such as shown in Fig. 5, wherein one terminal of the magnet 50 is connected by a conductor 55 to one side of a battery 56, and the remaining terminal of the magnet is connected by conductor 57 to one contact 58 of a dial switch having a normally open companion contact 59 connected by a conductor 60 with the return side of the battery, so that closing of the dial switch contacts 58 and 59 will energize the magnet and move the stop member 40 into blocking position.

The dial switch has its contact 59 normally held in open circuit position by a pin 61 on an indicating drum 62 arranged in the game conveniently to indicate to the player the number of free plays to which he is entitled, the drum or dial for this purpose having a series of indicia characters or numbers arranged along its periphery 63 for movement into indicating position by movement of the drum relative to an index 64.

The drum or dial 62 is mounted on a shaft 65 which is connected through a slip-clutch device 66 with a ratchet shaft 67. A driving pawl 68 mounted on an actuating armature 69 engages the teeth of a ratchet disc 70 rigid on the shaft 67 so that when the armature 69 is raised, the dial 62 will be turned away from its normal zero position a number of steps determined by the number of movements of the armature 69.

The driving ratchet for the dial is operated by a magnet 71 arranged to attract the pawl armature 69 and having one of its terminals connected by conductor 72 to one side of the battery 56 and by a conductor 73 to one of the contacts 15 of the game-operated or ball switch 13, the remaining contact 14 of which is connected by a conductor 74 to the return side of the battery.

When the player succeeds in lodging a ball into the pocket 12, the contacts 14 and 15 of a ball switch are closed, energizing magnet 71 and pulling up the pawl armature 69 to step the ratchet disc 70 once and move the dial 62 correspondingly, thus indicating, for example, one free play. This movement of the dial withdraws the pin 61 from engagement with the contact 59 of the dial switch, and the latter closes, thus energizing magnet 50 and moving the blocking or stop member 40 into blocking position beneath the dog or detent means on the coin slide, it being observed that the dial switch remains closed so long as the dial is out of zero indicating position. Having played the game to completion following deposit of a coin for this purpose, the player is aprired by the dial 62 of the number of free plays which he has to his credit, and he thereupon moves the control member or slide 19 inwardly without depositing another coin therein, and since the member 40 is in blocking position relative to the tail of the dog, the latter cannot move to project its nose into the coin pocket although there is no coin in the latter, and the slide is therefore permitted to move inwardly its full stroke to engage the shuffle arm 17 and release any balls for repeated play.

The arrangement is such that the dial 62 is stepped back once for each free play operation of the coin slide, mechanism for this purpose not being shown, it being pointed out, however, that the slip clutch 66 permits such retrograde movement of the dial so that when the latter is restored to normal position (whether by taking off the free plays by successive operation of the slide or by restoration of the dial by other master control means not shown), the magnet 50 will be de-energized to condition the game for further coin-controlled operation.

The objects and advantages of the invention may be realized by other forms of construction and other modes of operation of the constituent parts of the illustrative embodiment, and the invention is therefore not to be confined to any of the details or particulars set forth herein but is to be interpreted broadly in view of the appended claims which are expressly intended to include all equivalent arrangements.

Having thus described our invention, what we claim as new and desire to protect by Letters Patent is:

1. A device for permitting the operation of a coin slide having a coin aperture formed therein, without the deposit of a coin in the coin aperture of the slide, comprising a latching dog normally disposed in position to engage in the coin aperture to block the movement of the coin slide when no coin is deposited in the coin aperture of

the slide, means pivotally supporting the latching dog from an immovable part guiding the coin slide, an electromagnet support, an electromagnet on the support and having a movable armature comprising a plate member having an outer angled end portion to provide a stop adapted to be disposed in blocking relation with respect to the latch dog when the electromagnet is energized, and means for energizing said electromagnet.

2. In an auxiliary release means for a coin slide having a coin receiving aperture formed therein and guided for sliding movement on a frame, said coin slide being normally locked against full inward stroke by a spring urged latch dog pivotally arranged on the frame beneath the slide and normally disposed to bear against the latter to engage in the coin aperture and being normally released for full inward stroke by the deposit of a coin in the aperture to prevent the 20 latch dog from entering the same, said aux-

iliary release means comprising in combination, an electromagnet support adjacent said coin slide, an electromagnet on the support, a magnetically attractable armature for said electromagnet and arranged for movement relative to the latter on said support, a blocking means associated with said armature for movement with the latter and disposed to move into and out of blocking position relative to said latch dog, spring means normally urging said armature and blocking means out of blocking position relative to said latch dog, said armature and blocking means moving into blocking position relative to said latch dog to prevent pivotal movement of the latter into engagement with the coin aperture when said electromagnet is energized to attract said armature, and means including a switch for effecting energization of said electromagnet.
